UNITED STATES PATENT OFFICE.

UTLEY WEDGE, OF ARDMORE, PENNSYLVANIA, ASSIGNOR TO THE FURNACE PATENT COMPANY, OF PHILADELPHIA, PENNSYLVANIA, A CORPORATION OF PENNSYLVANIA.

DUST-COLLECTOR.

1,086,961.

Specification of Letters Patent. Patented Feb. 10, 1914.

Application filed May 9, 1910. Serial No. 560,320.

To all whom it may concern:

Be it known that I, UTLEY WEDGE, a citizen of the United States, residing in Ardmore, Pennsylvania, have invented certain 5 Improvements in Dust-Collectors, of which the following is a specification.

My invention consists of certain improvements in the dust collector for furnaces for which I filed application for Letters Patent 10 of the United States on the third day of January, 1910, Serial Number 535,995, the objects of my present invention being to provide for the uniform distribution of the gas throughout the entire body of dust-collecting material; to provide effective means 15 for removing the dust-collecting material from the chamber through which the gas is caused to pass and its return to said chamber, and to provide for the ready withdrawal of the removed dust. These objects I attain in the manner hereinafter set forth, reference being had to the accompanying drawings, in which—

Figure 1 is a view, partly in elevation and 25 partly in central longitudinal section, of the structural portion of a dust collector constructed in accordance with my present invention; Fig. 2 is a transverse section of the same on the line *a—a*, Fig. 1 showing 30 the structure charged with dust collecting material; Fig. 3 is a sectional plan view on the line *b—b*, Fig. 1; Fig. 4 is a transverse section on the line *c—c*, Fig. 3; Fig. 5 is a transverse section on the line *d—d*, Fig. 35 1; Figs. 6 and 7 are transverse sectional views of other forms of dust collector, embodying the main features of my invention. Fig. 8 is a perspective view of certain elements of the gas-distributing structure of 40 the apparatus, and Fig. 9 is a longitudinal sectional view of part of the structure which supports the lower end of the grate bars on which rests the mass of dust collecting material.

The main structure 1 of the separator 45 may be composed of concrete, brick work, or other material, and may be of any desired cross sectional form and length. The structure shown in Fig. 1 is of rectangular section 50 both longitudinally and transversely and is divided by a longitudinal partition wall 2 into a distributing chamber 3 and a separating chamber 4, the distributing chamber receiving the gas at one end from a flue 5 communicating with the furnace, and

the gas being delivered from the opposite end of the chamber 4 through a flue 6.

Extending transversely across the dust collecting chamber 4 are a series of short flues or ducts 7 of inverted U form, each of 60 these short transverse ducts communicating at one end with the distributing chamber 3. Each of the transverse ducts 7 is also connected to the adjoining duct by means of a series of short inverted troughs 9 at the 65 bottom of the duct, as shown in Fig. 2.

In the lower portion of the chamber 4 are a series of grated hoppers 10, each having inclined sides and inclined bottom, each of these grated hoppers being composed of 70 grate bars 11 hung at their rear or upper ends upon a straight notched bar 12 supported upon the partition wall 2, the front or lower ends of the grate bars being supported upon oppositely inclined bars 13 on 75 the front wall of the main structure.

The dust-collecting material is composed of substantially spherical bodies which will flow freely, and the chamber 4 is partially filled with these dust-collecting units, as 80 shown in Fig. 2, the transverse ducts 7 and cross troughs 9 being completely enveloped in said mass of dust-collecting units.

Gas entering the distributing chamber 3 is therefore caused to enter the cross ducts 7 85 and the connecting troughs 9 at the bottom of said ducts, consequently there is a free escape of gas around the lower edges of the ducts 7 and around the lower edges of the troughs 9, the result being a dissemination 90 of the gas uniformly throughout the entire mass of dust-collecting material contained in the chamber 4. A free flow of the gas through the chamber 4 is permitted while at the same time the gas is brought 95 into intimate contact with the dust-collecting units contained in said chamber and the course of the gas through the mass of dust-collecting material is so frequently interrupted and suffers such frequent change of 100 direction that ample time is afforded for the deposit of dust upon the dust-collecting units of the mass.

The mass of dust-collecting units contained in the grated hoppers 10 is relatively 105 free from the flow of gas and any dust which may be deposited upon the units contained in said hopper can find its way through the gratings and into the lower portion of the chamber 4, from which it can 110

be removed at intervals through cleaning openings provided in the sides, ends and bottom of said chamber for this purpose, similar openings being provided in the bottom of the distributing chamber 3 for the removal of any dust which may be collected in said chamber.

At the discharge end of each of the grated hoppers 10 is an outlet 15 provided with a movable cover, and from this outlet the dust-collecting units may be removed either continuously or at intervals so as to provide for the gradual descent of the mass of said units in the chamber 4, the units upon which dust has been deposited being dropped below that portion of the chamber through which the gas circulates, and, after discharging their dust through the grated hoppers 10, being removed through the outlets 15.

The outlet of each of the grated hoppers 10 communicates through a short spout 16 (Fig. 2) with an inclined runway 17 which discharges into a hopper 19, the latter delivering the dust-collecting units into the boot of an elevator trunk 20 which discharges said units at the top into inclined runways 21 which communicate with the interior of the chamber 4 through vertical spouts 22, as shown in Fig. 1, whereby the dust-collecting units are returned to said chamber. The position of the spouts 22 in respect to the casings 7 is shown by dotted lines in Fig. 3.

The flue 5 is divided into two parts by a central longitudinal wall 23 which aids in supporting the tiled top 24 of the flue, as shown in Fig. 4. When it is desired to conserve heat as in case the gas is directed to a Glover tower for the manufacture of sulfuric acid, the tiled top of the flue 5 may be overlaid with a mass 25 of asbestos or other material which is a poor conductor of heat, and the side walls of the flue may have air spaces 26 therein to prevent or restrict radiation of heat therefrom. The outlet flue 6 may be similarly constructed, as shown in Fig. 5.

In that form of my improved dust collector shown in Fig. 6, the casing 1^a is in the form of a vertical cylinder having a central gas supplying flue 5^a which communicates with the inner ends of a series of radiating flues or ducts 7^a embedded in the mass of dust-collecting material and having their lower portions connected by annularly arranged inverted troughs 9^a, the gas escaping under the lower edges of the ducts 7^a and troughs 9^a rising through the mass of dust-collecting material and finally escaping through the discharge flue 6^a.

Below the ducts 7^a is a grated hopper 10^a of inverted conical form, communicating at its lower portion with a centrally disposed

outlet pipe 15^a for the discharge of the dust-collecting units, the casing 1 having an inverted conical bottom 30 for directing the dust which passes through the grated hopper 10^a to an inclined discharge pipe 31.

That embodiment of my invention shown in Fig. 7 differs from the construction shown in Fig. 6, in having the bars of the grated hopper reversely arranged so as to discharge into an annular trough 32 on the exterior of the casing, the dust which passes through said grated hopper escaping through a central pipe 31^a at the bottom of the casing.

The gas distributing ducts 7^a may have openings disposed therein as desired, so as to provide for the escape of gas from said ducts in other directions than around the lower edges of the ducts.

I claim:—

1. A dust collector provided with a main chamber containing a mass of dust collecting units, a main gas passage, and a plurality of vertical casings extending transversely across the main chamber, each of said casings inclosing a chamber communicating at one end with the main gas passage and each of said chambers discharging independently of the others into the mass of dust collecting units.

2. A dust collector provided with a main chamber containing a mass of dust collecting units, a main gas passage, and a plurality of vertical casings extending transversely across the main chamber, each of said casings inclosing a chamber communicating at one end with the main gas passage and each of said casings being open at the bottom, whereby the gas escapes from the bottom of each casing independently of the others into the mass of dust collecting units.

3. A dust collector provided with a chamber containing a mass of dust collecting units, a main gas passage, and a plurality of casings distributed throughout the area of the main chamber, each of said casings containing a chamber communicating with the main gas passage, said casings being open at the bottom whereby the gas escapes from the bottom of each casing into the mass of dust collecting units, and the casings being connected by inverted troughs which also discharge at the bottom into the mass of dust collecting units.

4. A dust collector provided with a chamber whose lower portion is bounded by a grated hopper, gas discharging casings distributed throughout the area of the upper portion of said chamber, a continuous mass of dust collecting units contained in said chamber and filling the grated hopper thereof, and means for removing units from the bottom of the hopper whereby the dust will be separated from the dust collecting units

during the passage of the same over the gratings.

5. A dust collector provided with a chamber containing a mass of dust collecting units, means for distributing the gas throughout said mass, and a grated hopper in the lower portion of the chamber, said hopper consisting of independent bars engaging a straight bar at the back of the

hopper and oppositely inclined bars at the 10 front of the hopper.

In testimony whereof, I have signed my name to this specification, in the presence of two subscribing witnesses.

UTLEY WEDGE.
